UNITED STATES PATENT OFFICE.

ALBERT R. PRITCHARD, OF ROCHESTER, NEW YORK.

DESIGN FOR A SPRAYER-BODY.

SPECIFICATION forming part of Design No. 30,530, dated April 11, 1899.

Application filed March 15, 1899. Serial No. 709,217. Term of patent 7 years.

To all whom it may concern:

Be it known that I, ALBERT R. PRITCHARD, a citizen of the United States, and a resident of Rochester, in the county of Monroe and State of New York, have invented and produced a certain new and original Design for a Sprayer-Body, of which the following is a specification.

This invention relates to a design for a sprayer-body, and the accompanying drawing shows a perspective view thereof.

The leading or material feature of the design consists in the new, useful, and original shape thereof.

15 The design consists in the cylindrical por-

tion A and the dependent portion B, in the form of a truncated cone, having its smaller diameter upward and adjacent to the end of the cylindrical portion A and arranged so that said cylindrical portion A is set at an angle to a plane intersecting the axis of the truncated cone at right angles, substantially as shown.

20 What I claim is—

The design for a sprayer-body, substantially as herein shown and described.

ALBERT R. PRITCHARD.
